AUTOMATIC APPARATUS FOR ARTIFICIAL
RESPIRATION

Robert Kubán and Zdeněk Kalenda, Prerov, Czechoslovakia, assignors to Meopta, národní podnik, Prerov, Czechoslovakia

Filed Feb. 2, 1961, Ser. No. 86,793
7 Claims. (Cl. 128—29)

The present invention relates to an automatic apparatus for artificial respiration and more particularly to an apparatus which provides positive pressure for inhaling and negative pressure for exhaling.

An object of the invention is the provision of automatic apparatus for artificial respiration which meets a wide variety of requirements, and which is truly universal in its applicability. Another object is to provide artificial respiration apparatus independent of a source of electrical energy for an independent electric drive is employed for the vacuum pump. Yet another object is the easy control of all important functions of the apparatus so that it may be used for patients of all ages. A further object is an overall arrangement of the structural members in the apparatus which results in small dimensions and low manufacturing costs.

The exact nature of this invention as well as other objects and advantages thereof will be readily apparent from consideration of the following specification relating to the accompanying drawings, wherein

FIG. 1 is a partly sectional elevational view of certain elements in an automatic apparatus for artificial respiration according to the invention, during the exhaling phase.

FIG. 2 shows the apparatus of FIG. 1 during the inhaling phase.

FIG. 3 is a diagrammatic representation of an embodiment during the inhaling phase of the apparatus.

FIG. 4 shows the apparatus of FIG. 3 during the exhaling phase.

FIG. 5 is a diagrammatic representation of another embodiment of the invention equipped with a vacuum pump.

FIG. 6 is a view of the control panel of an apparatus based on the principle shown in FIGS. 3 and 4, the apparatus being partially shown in section.

FIG. 7 is a cross-section through the mechanism of the apparatus taken in the plane Y—Y in FIG. 6.

FIG. 8 is a cross-sectional view taken along the line X—X in FIG. 6, and

FIG. 9 is a cross-sectional view of the apparatus taken along the line Z—Z in FIG. 6.

The basic features of an automatic apparatus for artificial respiration according to the invention are shown in FIG. 1 in the exhaling and in FIG. 2 in the inhaling phase. In the body T of the apparatus two conduits are connected to a pressure chamber M in which a piston I having a piston rod K is movably arranged. The conduits also communicate with a flexible tube P which is attached to a non-illustrated mask. Two three-way cocks V₁ and V₂ are arranged in respective conduits between the chamber M and the tube P. The cock V₁ is connected by a tube to an oxygen flask O. The other cock V₂ is connected to a vacuum pump S. Other valves may be used instead of the three-way cocks shown in the drawing. The exhaled mixture of gases is drawn off the patient's lung by the vacuum pump S. In addition to the three-way cocks V₁, V₂ the conduits in the body T are provided with reducing valves R₁, R₂, R₃, R₄ by means of which the operation of the apparatus can be controlled as will presently become apparent.

The three-way valves V₁ and V₂ are controlled by the pressure of compressed air or oxygen from the flask O and by the underpressure produced by the vacuum

2

pump S, and the apparatus is automatically switched between inhalation and exhalation by a change-over switch (not shown in the drawing). The alternating vacuum and pressure which actuate the change-over switch is created in the pressure chamber M by the movement of the piston I by the gas admitted from the flask O through a reducing valve L, or by the vacuum pump S.

Throttling of the admission of compressed gas to the pressure chamber M by the reducing valve R₁ controls the length of the exhalation period. The throttling of the suction line from pressure chamber M by the reducing valve R₂ controls the length of the inhalation period. The reducing valve R₃ between the oxygen flask O and the tube P controls the admission of gas to the lungs and thus the inhaled volume. The valve R₄ in the vacuum line controls the exhaled volume. The apparatus operates during inspiration under-pressure and during expiration under the suction of the vacuum pump S.

FIG. 3 shows diagrammatically the automatic apparatus according to the invention with the change-over switch for the valve-system during the inhaling phase when oxygen, or compressed air, from the flask flows through the conduit 1 of the reduction valve, not shown in FIG. 3, and open shut-off valve 2 to a supply tube 6 and connector tube 10, whereupon it enters the mask. Due to the underpressure produced by the vacuum pump connected to a pipe 11, oxygen is sucked off through a discharge tube 8 over the open shut-off valve 3 from an accordion-type bellows 12, whose movable wall during its displacement shifts a rod 13 in the direction of the arrow 15. The rod 13 is slidably mounted in a bearing 14, an abutment 16 acting on a disc or spring cap 17 against the pressure of a spring 18. During its shifting movement the disc 17 strikes a two-armed stop lever 19, which is biased by a helical spring 20. The two-armed lever 19 is provided with a catch 21, which, after its release, permits an automatic sliding movement of a slide 22 under the influence of the compressed spring 18. During this movement the valves 2 and 3 are closed, and the shut-off valves 4, and 5 are opened by means of arms 23, 24 and 25 arranged on the slide 22.

FIG. 4 shows the apparatus of FIG. 3 in the exhalation phase, when the vacuum pump is attached to the pipe 11 in such a manner that through the open valve 5 in the suction tube 9 and the connector tube 10 it aspirates the air from the patient's lungs. At the same time oxygen or compressed air from the flask is admitted through the pipe 1, the feed conduit 7, and open valve 4 to the accordion type bellows 12, which is thus filled and shifts the rod 13 in the direction of the arrow 26 until the abutment 16 actuates the disc or spring cap 27 against the influence of the spring 28. During its movement the disc 27 abuts against the two-armed stop lever 29 which is biased by a helical spring 30. This two-armed lever 29 is provided with a catch 31, which—when released—permits automatic movement of the slide 22 by the action of the compressed helical spring 28.

The slide 22 carries arms 23, 24 and 25 which open the valves 2 and 3 and close the valves 4 and 5. In the tubes 7 and 8 near the accordion-type bellows 12 there are provided two reducing or control valves 32 and 33, and in the neighborhood of the tube 10 two reducing or control valves 34 and 35. Mounted in the same tubes are safety valves 36 and 37 which limit pressure and vacuum.

FIG. 5 shows a second embodiment of the invention. The operation of this apparatus does not require a separate vacuum pump. The apparatus is controlled by a change-over switch comprising a slide 38 and a slidable rod 39 provided with an abutment 40, which during movement in one direction strikes against a disc 41 acted upon by a helical spring 42, whereas during movement in the other direction it strikes against a disc 43

cooperating with a helical spring 44. The disc 41 deflects in its movement a two-armed lever 45 biased by a helical spring 46 and provided with a catch 47. The disc 43 deflects a two-armed lever 48 biased by a helical spring 49 and provided with a catch 50.

The slide 38 is provided with arms 51, 52 and 53 for actuating valves 54, 55, 56, 57, 58 and 59. The rod 39 is slidable in bearings 60 and 61 and is connected to a pair of pistons 62 and 63 mounted in tandem in a cylinder 64 which is connected by conduits 65, 66 and 67 to the various valves. The cylinder 64 encloses three pressure chambers Q, U, Z whose volumes change upon displacement of the pistons 62 and 63. Compressed oxygen from a non-illustrated flask is admitted through a pipe 63 to the valve 56 and to a space between the valves 58 and 59. When the valve 56 is opened, oxygen is fed to the patient's lungs through a conduit 69.

The conduits 69 and 70 lead to the patient's mask and are provided with safety valves 71 and 72 which limit positive and negative pressure. A reducing valve 73 in the conduit 69, a reducing valve 74 in the conduit 70, and reducing valves 75, 76 in conduits 66 and 67 are provided for control purposes as described above.

The automatic respiration apparatus shown in FIG. 5 operates as follows:

During the inhaling phase, compressed oxygen flows through the conduit 63, the valve 56 and conduit 69 to the mask and the patient's lungs and through the open valve 59 and conduit 67 to the pressure chamber U, the space of which is enlarged by movement of the piston 63. Gas escapes during this movement from the chamber Q through the exhaust valve 77 to the outside. From the chamber Z the gas escapes through the conduit 66 and the open valve 55. When the rod 39 with the abutment 40 is displaced, the disc 43 is shifted and the two-armed lever 48 carrying the catch 50 is pivoted. When the catch 50 is released, the slide 38 is moved in the direction of the arrow "m" by the helical spring 44. During this movement the arm 53 closes the valves 55 and 59; simultaneously the arm 52 opens the valves 54 and 58 and the arm 51 opens the valve 57 and closes the valve 56, thereby initiating the inhaling phase. Compressed oxygen flows then through the tube 68, valve 58 and conduit 66 to the chamber Z, and the resulting displacement of the piston 63 actuates the changeover switch of the control valves. Due to the underpressure generated in the chamber Q, the mixture from the patient's lungs is exhausted through the conduit 65, valve 57 and conduit 70.

An automatic respiration apparatus based on the principle shown in FIGS. 3 and 4 is illustrated in FIGS. 6 to 9.

The casing 78 of the apparatus is provided with a cover 79 and knobs 80, 81, 82 and 83 for control of the reducing valves. Further, arranged on the cover 79 are knobs 84 and 85 for setting the safety valves which limit pressure and suction. The knobs are arranged in the groups respectively consisting of the knobs 81, 83 and 85 which control the exhaling phase, and the knobs 80, 82 and 84 which control the inhaling phase. The knobs 80 and 81 which control the length of the individual phases are placed above one another.

The apparatus is connected to the vacuum pump by a tube 86 and to the oxygen flask by a tube 87. A tube 88 and a tube 89 are connected to the mask.

One of the control valves is shown in detail in the sectional view of FIG. 7. A valve member 90 is slidably mounted in a guide 93 to control fluid flow between the accordion-type bellows 91 and the tube 92 joined to the mask. The valve member cooperates with a valve seat 94 and is biased toward the closed position by a helical spring 95.

FIG. 7 shows also one of the reducing valves arranged between the accordion-type bellows 91 and the tube 92. The knob 80 is attached to a threaded needle whose conical tip 96 cooperates with a conforming valve seat 97.

A guide 98 for the valve needle is resiliently secured by a yoke 99.

FIG. 6 shows details of one of the safety valves provided with the control knob 83 (FIG. 9). The control knobs 83 and 84 of both safety valves are adjustable in longitudinal slots of the cover 79 along respective scales. One of the slots 100 and one of the scales 101 are shown in FIG. 6. A pin 102 associated with the control knob 83 (FIG. 8) is guided in a bifurcated end of a lever 103 pivotally mounted on a pin 104. The shorter arm of the lever 103 is engaged by a helical spring 105 whose other end is attached to the operating lever 106 of a safety valve flap 107 provided in the conduit 86 between the vacuum pump and the tube 88 connected to the mask.

The change-over switch for the control valves is shown in FIG. 8. A rod 109 is attached to a movable wall 108 of the accordion-type bellows 91 and carries an abutment 110 which during its reciprocal movement actuates discs 111 and 112 biased by helical springs 113 and 114. The discs 111 and 112 control levers 115 and 116 which are connected by a helical spring 117. The levers 115 and 116 are provided with cylindrical catches 118 and 119 adapted to alternately engage the edges of a slide 120 which is equipped with arms 121 and 122 (FIG. 9), said arms actuating the various control valves, provided in the automatic respiration apparatus.

We claim:

1. In a respiration device, in combination:
  - (a) expandable container means including a fixed wall and a wall reciprocable relative to said fixed wall in a predetermined path to vary the volume of a gas space in said container means;
  - (b) a source of gas under pressure;
  - (c) a source of suction;
  - (d) a feed conduit communicating with said source of gas and with said gas space;
  - (e) a discharge conduit communicating with said gas space;
  - (f) connector means for connecting said device to respiration mask means;
  - (g) a gas supply conduit communicating with said source of gas and with said connector means;
  - (h) a suction conduit communicating with said source of suction and with said connector means;
  - (i) four shut-off valve means, each valve means being reciprocable in a respective one of said conduits in a path parallel to said predetermined path between a conduit closing and a conduit opening position; and
  - (j) abutment means operatively connected to said movable wall for movement therewith in a path parallel to said path, and abuttingly engageable with said shut-off valve means for moving the same between said positions thereof when said movable wall moves relative to said fixed wall, said abutment means including
    - (1) an abutment member fixedly connected to said wall for joint movement therewith,
    - (2) slide means reciprocable between two operative positions thereof in a path parallel to said predetermined path,
    - (3) two releasable stop means for respectively limiting movement of said slide means toward said operative positions thereof in respective intermediate positions,
    - (4) two yieldably resilient members extending from said abutment member in opposite directions parallel to said predetermined path, said resilient members being interposed between said abutment member and respective portions of said slide means for actuating movement of said slide means responsive to said movement of said abutment member, whereby said slide means moves with said abutment member between said intermediate positions thereof when said abutment member moves between correspond-

ing positions, and said resilient members are compressed when said abutment member moves beyond said corresponding positions while said stop means limit movement of said slide means, (5) motion transmitting means interposed between said abutment member and each of said stop means for respectively releasing said stop means responsive to movement of said abutment member a predetermined distance beyond a respective corresponding position thereof, and (6) arm means mounted on said slide means for joint movement therewith parallel to said predetermined path and engageable with said shut-off valve means for moving the same between said positions thereof.

2. A device as set forth in claim 1, further comprising adjustable control valve means for controlling the rate of flow of said gas in said conduits.

3. A device as set forth in claim 1, wherein said discharge conduit communicates with said source of suction.

4. A device as set forth in claim 1, wherein said source of suction includes pump means connected to said movable wall for actuation thereby.

5. A device as set forth in claim 1, wherein said slide means is movably mounted on said abutment member.

5 6. A device as set forth in claim 1, wherein said motion transmitting means include spring cap means interposed between said abutment member and each of said resilient members.

10 7. A device as set forth in claim 1, wherein said stop means each include a lever member movable between a movement limiting position and a releasing position, and a resilient member connecting said lever members for urging the same toward said movement limiting positions thereof.
